OF TOLEDO, OHIO, A CORPORATION OF OHIO

MOLD AND METHOD OF FILLING THE SAME

Application filed June 13, 1927. Serial No. 198,465.

This invention relates to a method of casting metal and apparatus therefor. The purpose of the invention is to fill a mold with metal quickly, and without the production of excessive eddy currents within the mold. More specifically, the purpose of the invention is to utilize relative horizontal movement of the mold and molten metal in filling the mold, particularly in combination with evacuation of air from the mold during the filling thereof, and to avoid unequal filling of the mold which would otherwise result from relative horizontal movement of the mold and molten metal in the direction of an elongated horizontal inlet opening in a mold.

Further details of the invention will appear as the description proceeds.

In the accompanying drawings forming a part of this specification, Figure 1 is a diagrammatic plan view of apparatus suitable for carrying out the method; Fig. 2 is a section on the line 2—2 of Fig. 1, showing one mold-half in elevation.

In the embodiment of the invention illustrated in the drawings, a mold 10 is mounted upon a carrier 11 for revolution about an axis 12. Arrow 13 on Fig. 1 indicates the direction of movement of the mold about its axis.

Beneath the path of the mold there is a metal container 14 having a slot 15 in its upper side through which the bottom of the mold may contact molten metal 16 within the container.

The mold cavity 17 is connected by a narrow slit between the mating sections with a vacuum groove 18 in the face of the sections. Air is exhausted from this vacuum groove and so from the mold cavity by any suitable means, not shown.

At the bottom of the mold there is an inlet opening 19. This inlet opening is preferably elongated in the direction of movement of the mold, and across the inlet opening there are a plurality of partitions 20. The bottoms of these partitions slant forward in the direction of movement of the mold. The forward end 21 of the mold inlet likewise slants forward, and so does the rear end 22 of the mold inlet. It will be readily seen that the molten metal will tend to slide

up the partitions at 23 when the mold is moved in the direction of arrow 24 on Fig. 2.

Slanting the bottom of the inlet forward in the manner described, tends to scoop up the metal when relative horizontal movement is produced between the mold and the metal. This minimizes the differential pressure on the metal within the mold and outside thereof necessary to fill the mold cavity, as the influx of the metal in the mold is assisted by this scooping action. At the same time it renders the beginning of the influx of the metal into the mold more prompt and retards the tendency of the metal to flow downward from the inlet when the mold is raised above the molten metal in the container, thus lengthening appreciably the effective filling time for the mold. Furthermore, when the opening is elongated in the direction of travel of the mold, the partitions tend to equalize this scooping action along the length of this inlet so that the forward end of the mold cavity is filled substantially at the same time and evenly with the rear end of the mold cavity.

It will be understood that variations in the shape and arrangement of the mold and in the scooping partitions in the inlet are within the scope of this invention, being dependent upon the shape of the article to be cast. It will also be apparent that, with a stationary mold, horizontal movement of the metal container, or of the metal in the container, produces substantially the same result as horizontal movement of the mold where the metal is stationary, as either the mold or the metal may be moved, or both may be moved, the relative motion of the metal and the mold being the only requisite for producing the described effect. It will also be apparent that sufficiently rapid relative movement of the mold and metal in proportion to the height of the mold cavity above the level of the metal outside of the mold will result in completely filling the cavity without the aid of differential pressures, although the combination of the two forces for filling the mold is preferred.

It will be further understood that, where there is relative horizontal movement be-

- tween the mold and the metal, and the inlet is elongated in the direction of such movement, partitions across the inlet tend to equalize the distribution of the metal even if such partitions are vertical, because they prevent the flowing of the metal to the rear of the mold and cause it to rise substantially equally through each of the plurality of inlets formed by said partitioned inlet.
- 10 Various other modifications may be made within the scope of the appended claims.
- What I claim is:
1. The method of filling a mold with molten metal, which comprises producing relative horizontal movement between the mold and the metal, and utilizing said horizontal movement to raise the metal into the mold cavity, by means of a surface slanting downward from the mold cavity and forward in the direction of mold travel.
  2. The method of filling a mold with molten metal, which comprises arranging the mold with its inlet downward and immersed in molten metal, producing relative horizontal movement between the mold and metal with the inlet directed downward and forward in the direction of mold travel so that said relative movement tends to scoop the metal into the mold.
  3. The method of filling a mold with molten metal, which comprises arranging the mold with its inlet downward and immersed in molten metal, producing relative horizontal movement between the mold and metal with the inlet directed downward and forward in the direction of mold travel so that said relative movement tends to scoop the metal into the mold, and completing the filling of the mold by exhausting air from the mold cavity.
  4. A mold having an inlet opening in its bottom, a container for molten metal, and means permitting relative horizontal movement between the mold and the container, the bottom end of the inlet in the mold slanting in a direction to cause said relative movement to force metal upward into the mold.
  5. A mold having an inlet opening in its bottom, a container for molten metal, and means permitting relative horizontal movement between the mold and the container, the bottom end of the inlet in the mold slanting in a direction to cause said relative movement to force metal upward into the mold, the inlet being elongated in the direction of said relative movement and there being partitions across said inlet, said partitions slanting in a direction to aid in the lifting of the metal into the mold.
  6. A mold having an inlet opening in the bottom thereof and a passage leading upward from said opening to the casting cavity, a container for molten metal, means for permitting relative horizontal movement between the mold and the metal, said inlet and

passage being elongated in the direction of said relative movement, and partitions across said passage dividing it into a row of passages.

7. A mold having an inlet opening in its bottom, a container for molten metal, and means permitting relative horizontal movement between the mold and the container, the bottom end of the inlet in the mold slanting in a direction to cause said relative movement to force metal upward into the mold, and connections for exhausting the air from the mold cavity.

8. A mold having an inlet opening in its bottom, a container for molten metal, and means for permitting relative horizontal movement between the mold and the container, the bottom end of the inlet in the mold slanting in a direction to cause said relative movement to force metal upward into the mold, the inlet being elongated in the direction of said relative movement and there being partitions across said inlet, said partitions slanting in a direction to aid in the lifting of the metal into the mold, and connections for exhausting the air from the mold cavity.

9. A mold having an inlet in the bottom thereof, a container for molten metal, means for permitting relative horizontal movement between the mold and the metal, said inlet being elongated in the direction of said relative movement, and partitions across said inlet forming a row of inlets arranged in the line of said relative movement, and connections for exhausting the air from the mold cavity.

10. A mold having an inlet opening in its underside and a passage slanting at an angle to the vertical upward from said opening to the casting cavity, and a mounting for the mold permitting relative horizontal movement between the mold and molten metal in contact with the bottom of the mold around said opening.

11. A mold having a horizontally elongated inlet opening in its underside, the passage leading upward from said opening to the casting cavity and partitions across the passage, said partitions being at an angle to the vertical and all slanting in the same direction.

12. A mold having an inlet opening in its underside, said inlet opening being elongated horizontally, and a passage leading upward from said opening to the mold cavity and a fin on the side of the inlet opening arranged at an angle to the vertical, and a mounting for the mold permitting relative horizontal movement between the mold and molten metal in contact with the bottom of the mold around said opening.

In testimony whereof, I have hereunto signed my name to this specification.

RALEIGH MINKE.
